TIME BASE GENERATOR

Nelson N. Estes and James J. Moore, Austin, Tex., assignors to Union Carbide Corporation, a corporation of New York

Filed Nov. 28, 1958, Ser. No. 777,011

3 Claims. (Cl. 317—231)

This invention relates to a time base generator, that is a device which generates a signal having a known desired relationship to time.

For certain applications it is desired to have a time base against which signals can be compared. For example, if it is desired to study a voltage or current as a function of time, a time base is necessary. Devices for producing time bases are referred to as "time base generators." A time base generator can produce an output voltage or current which is any function of time, linear or exponential.

A family of electrochemical devices in which a number of different effects are achieved by the movement of ions in solution has recently attracted favorable attention. These devices have come to be known as "solions." They are discussed in some detail in the literature: Journal of the Electrochemical Society, vol. 104, No. 12 (December 1957); Yale Scientific Magazine, vol. XXXII, No. 5 (February 1958) and Electronics Products Engineering Bulletin No. 1, published November 1957, by National Carbon Company, 30 East 42nd Street, New York 17, New York.

In application Ser. No. 717,676 filed February 26, 1958, by Richard N. Lane and James J. Moore reference is made to a particular type of solion referred to as an "integrator." This device has the ability to indicate the integral of a current applied to it over a period of time. One type of integrator is provided with electrodes so that its signal can be read electrically; it is termed an "electrical read-out integrator." The present invention employs such a device as its essential component; its construction and function will be explained below.

The principal object of the invention is the provision of a time base generator employing an electrical readout integrator, which generator is particularly adapted to the production of time bases of long duration. It will be discussed with reference to the accompanying drawing in which:

FIG. 1 is a circuit diagram of a time base generator embodying the invention; and

FIG. 2 is a diagram of a modified circuit.

The invention is a time base generator comprising the combination of an electrical readout integrator, a suitable current source, and a two-position switch. In one position the switch connects the current source to the input electrodes of the integrator (the input electrode and the common electrode) and in the other position disconnects the current source from the integrator. In the first position the switch connects a bias voltage between the common electrode and the readout electrode of the integrator and in the other position connects the bias voltage across the input electrode and readout electrode of the integrator to clear it.

The time base generator of the invention is capable of producing an output voltage or current which is any function of time, linear or exponential depending upon the input current. For a linear function, a constant current input is required. For an exponential function, an exponential input current is required. For the sake of conciseness, the invention will be described with particular reference to production of a linear time base.

An electrical readout integrator as the term is used herein is a solion consisting of a cell containing as electrolyte a solution of a reversible redox system, the solu-

2

tion being divided into three zones of different concentration of a measured species of such system, all zones being electrically connected through the electrolyte. One of the three zones is of variable concentration. It is called the "integral" zone. It is provided with two electrodes, one termed the "Common" electrode, or integrator anode, the other the "Readout" electrode, or integrator cathode. Another zone of concentration which is high in concentration of the measured species is referred to as a "reservoir" zone. It contains an electrode termed the "Input" or reservoir electrode. Separating the integral zone and the reservoir zone is a zone dilute in the measured species of the redox system. It is provided with an electrode called a "Shield" or scavenger electrode.

In operating an electrical readout integrator, a biasing voltage is applied across the common and readout electrodes, the common electrode being made the anode of the circuit, so as to furnish the readout current which is proportional to the concentration in the integral zone. A similar biasing voltage is applied across the shield and input electrodes, the latter being made the anode so as to maintain a high concentration of measured species in the reservoir zone and to clear the dilute zone of any ions of the measured species which may have escaped into it from the integral zone. With these electrodes biased as described, when a source of current is connected across the input electrode and the common electrode so that the latter is the anode, the concentration of the measured species of the redox system is increased in the integral zone. The increase can be read electrically on a suitable meter in the biasing circuit of the integral zone. When the current source is disconnected, the increased concentration of measured species is maintained in the integral zone by reason of the configuration and location of electrodes in that zone, and when the source is again connected, again an increase in concentration is noted. Thus, the device integrates the current applied over a period of time. When the bias voltage is applied between the input electrode and the readout electrode so as to make the input electrode positive with respect to the readout electrode, the iodine concentration in the integral zone is decreased and thus the integrator is "cleared."

Referring now to FIG. 1 of the drawing, an electrical readout integrator E is diagrammatically represented. A biasing voltage is provided by a circuit including a battery B₁, the voltage being applied between the input electrode I and the readout electrode R when a two-position switch S₁ is in one position (position 1 or "clearing position") and between the common electrode C and the readout electrode R of the integrator when the switch S₁ is in the other of its two positions (position 2 or "integrating position"). When the switch S₁ is in the second position, the common electrode C is the anode of the biasing circuit, and when it is in the first position, the input electrode is the anode of the biasing circuit.

In the readout biasing circuit including the battery B₁ a network including a negative temperature coefficient resistance 10 which is connected in parallel with a series-connected ammeter 12 and resistor 14 is provided. The purpose of this network is to maintain the slope of the time base output constant for a given input over a normal operating temperature range. A resistor 15 is provided between the battery B₁ and the common electrode C of the integrator E to prevent excessive fluctuation in the readout signal when the switch S₁ is moved from position 1 to position 2.

A bias voltage is applied across the shield electrode S and the input electrode I of the integrator from a battery B₂. The battery B₂ is so connected as to make the input electrode I the anode of the circuit.

The constant current source which produces the input signal to the integrator E includes a battery B_3 , any one of a number of resistors $16, 18, 20$ and a multi-position switch S_2 . When the switch S_1 is in proper position (position 2), the constant current source is connected in series with the input electrodes of the integrator by connecting the switch S_2 to the desired one of the resistors $16, 18, 20$. The purpose of providing a plurality of resistors in the circuit is to provide for a plurality of time bases of different lengths. As many resistors may be provided as desired. When the switch S_1 is in position 1, the constant current source is disconnected from the integrator.

The device illustrated by FIG. 1 is a linear device. By inserting a capacitor 22 of appropriate capacitance with regard to the battery B_3 and the resistors $16, 18, 20$ between the switch S_2 and position 2 of switch S_1 as shown in FIG. 2 a derivative time base is produced.

Illustrative of the invention, a time base generator embodying its principles was constructed in which the battery B_1 and the battery B_2 both had a voltage of 0.9 volt and the battery B_3 had a voltage of 24 volts. The resistors $16, 18, 20$ had resistances of 0.68 megohm, 6.8 megohms and 68 megohms respectively. The resistor 15 had a resistance of 10 megohms.

Using an "X-Y" recorder of commercial manufacture with a sensitivity of $6\frac{2}{3}$ microamperes per inch on the X axis linear time bases of 5 seconds per inch, 50 seconds per inch and 500 seconds per inch respectively were produced when resistors having the resistances just enumerated were connected to the integrator.

A full description of an electrical readout integrator suitable for use in the amplifier of the invention is found in the application of Nelson N. Estes, Ser. No. 777,009 filed concurrently herewith, now U.S. Patent No. 3,021,482, issued February 13, 1962.

We claim:

1. A time base generator comprising the combination

of an electrical readout integrator, a source of input current, and a two-position switch, said electrical readout integrator being a solution consisting of a cell containing as electrolyte a solution of a reversible redox system, said solution being divided into three zones of different concentration of a measured species of such system, one of said zones being of variable concentration and having two electrodes, one termed the "common" electrode of said integrator, the other the "readout" electrode of said integrator, a second of said zones of concentration being high in concentration of said measured species of said reversible redox system and having an electrode termed the "input" electrode of said integrator, and the third of said zones being dilute in said measured species of said reversible redox system and having therein an electrode termed the "shield" electrode of said integrator, said integrator having a readout circuit including said readout electrode and said common electrode, said switch in one position connecting said current source to said input electrode and common electrode and a bias voltage between said common electrode and readout electrode of said integrator, and in the other position disconnecting said source and voltage therefrom and connecting said voltage to said input electrode and readout electrode of said integrator to clear the same.

2. A generator as defined by claim 1 in which a resistor having a negative temperature coefficient is connected in the readout circuit of said integrator.

3. A generator as defined by claim 1 in which said input current source is a constant current source.
